MEANS FOR DIMMING RADIO LIGHTS

John L. McWeeny, Chicago, Ill.

Application November 19, 1936, Serial No. 111,707

5 Claims. (Cl. 250—20)

My invention relates to radio receiving sets and particularly to means for automatically dimming the dial light thereof after a predetermined period of brightness.

In the use of radio receiving instruments it is not necessary for the dial light to shine brilliantly during the entire time of operation, since it is needed only for the short period when the tuning dial is being adjusted for the reception of a desired station. Full time illumination results in unnecessary current consumption, and this is important in battery-operated sets such as used in automobiles, and, in addition, is objectionable in other respects. It is considered sufficient, for all practical purposes, to provide merely a dim glow, at other times than when tuning, sufficient to show that current is being supplied to the instrument. At that time the full brilliancy of the lights is desirable, the lights becoming dim immediately thereafter, all without the volition of the user.

In the apparatus herein disclosed, I have provided simple means for accomplishing the desired result. In one exemplification I connect the circuit-making and breaking element to the shaft for operating the variable condenser, the connection being so made that whenever the shaft is rotated to any substantial degree the dial light is intensified; shortly thereafter the light circuit is changed to cut in resistance that serves to substantially reduce the intensity of the light and the amount of current consumed.

In another embodiment of the idea a simple push button may be employed, independent of the tuning mechanism, the movement of the button serving to set in motion the necessary instrumentalities that will bring about the desired result. In whatever form used, the subsequent dimming of the lights is brought about automatically and the lights will remain dim until the current to the set is interrupted or a new manual act is performed by the operator.

The invention will be more readily understood by reference to the accompanying drawing, in which,

Fig. 1 is a sectional view through a form of apparatus such as contemplated;

Fig. 2 is a wiring diagram for the apparatus shown in Fig. 1; and,

Fig. 3 is a wiring diagram showing means operable by a push button for accomplishing the desired result.

In the example shown in Figs. 1 and 2 I provide, on the shaft 10, for operating a variable condenser or other tuning mechanism, a magnet con-

sisting of the field 11 fixed on a bracket 12 to the chassis 13 of the set. The armature 14 is reciprocable on pins 15, springs 16 serving to separate the parts except when energized. Contacts 17 are closed by a contact piece 18 carried by the armature, the armature being carried on a sleeve 19 and being nonrotatable. The sleeve holds a disc 20 rotatable on the sleeve, the disc carrying a contact piece 21 adapted to alternately close contacts 22 and 22a. The disc 20 is normally in face-to-face contact with a disc 23 fixed to the shaft 10, sufficient friction being provided between the two discs due to the force of the springs 16, to insure that whenever the shaft is turned, the contact disc 20 will, likewise, be turned to close other contacts, such as 22a, by the contact piece 21. When the magnet is energized, the discs 20—23 are separated.

Referring now to the diagram of Fig. 2, two dial lights 24 are shown, the current being supplied from the line 25 thence through the contact piece 18, the line 26, then through the lamps to the return line 27. When the contacts 17 are broken as by the displacing of the contact piece 18, the circuit is through the resistance 28 and the lights are dimmed.

As a means for bringing about the breaking of the circuit through the contacts 17, I provide an A. C. or D. C. magnet, the field and armature of which are indicated at 11 and 14 in the diagram. Current is supplied from the line 25 and branch 29, through the coils and to the shiftable switch element 30 whereby one or the other of the branches 31—32 is energized, each of said branches containing heat generating resistance 33—34. Bimetal or other thermo-sensitive elements 36—37 are located adjacent to the resistance elements, the heat generated by said resistance serving to shift the switch arm 30 from one to the other of the contact pieces 38—39. The contacts 22—22a, only two pairs of which are shown in the diagram, are adapted to be alternately closed by the contact piece 20 and to complete a circuit through the return line 27.

In operation, assuming a movement of the shaft 10 for tuning, a pair of contacts 22 will be closed as indicated by the dotted lines in Fig. 2. Current will pass through the branch 31 and the magnet, thus moving the armature 14 into position to close the contacts 17 and to supply current at full voltage to the lamp or lamps. Immediately the resistance element 33 will begin to heat and the thermostatic device 36 will move and shift the switch arm 30 out of contact with the piece 38 and into contact with the piece 39. 55

Breaking the circuit through the branch 31 will de-energize the magnet and break the contacts 17, the current then passing to the lights through the resistance 28 and remaining in this condition 5 until a subsequent tuning serves to close the second pair of contacts 22a and to repeat the operation through the branch 32 of the circuit.

In the construction shown in the diagram of Fig. 3, the parts remain the same except for the 10 automatic feature. In that construction a push button 40 serves to move a switch arm 41 into engagement with a contact 42, the switch arm being retained in contact-making position by the latch 43. However, the resistance element 44 15 immediately generates heat and causes movement of the thermo-sensitive element 45 with consequent tripping of the latch 43 and the breaking of the circuit. With the circuit broken the current will be delivered to the light through the resistance 28 as heretofore described. In 20 the last named construction the operator must push the button whenever he wishes full light, the return to dim light being automatically brought about.

25 It will be understood that I have illustrated only typical apparatus and that modifications may be made in many of the features without departure from the spirit of my invention.

I claim:

30 1. In means of the class described, the combination of a light circuit having a switch, said circuit having resistance therein when the switch is open, and means for controlling said switch including a magnet having a movable part, a circuit for energizing said magnet to move said part and close said switch and short circuit said resistance, means for closing said last named circuit, said last named circuit including a thermo-resistance for generating heat, and a thermostat 35 positioned to be affected by said heat and acting to break said last named circuit after the expiration of a predetermined time, whereby to de-energize said magnet and open said switch and thereby to place said resistance in circuit 40 with said light.

45 2. In light control apparatus for radio receiving sets, the combination of a light and a circuit for energizing the same, a circuit breaker in said circuit, resistance across the poles of said circuit breaker, and means for actuating said circuit breaker, including a magnet, the armature of which is connected to the circuit breaker, a second circuit for energizing said magnet whereby to effect the closing of said circuit breaker, means 50 for closing said second circuit, said second circuit including resistance for generating heat, a thermo-sensitive element in position to be affected by said heat, and a switch operated by said element to break said second circuit after a pre- 55 determined time.

3. In light control apparatus for radio receiving sets, the combination of a light and a circuit for energizing the same, a circuit breaker in said circuit, resistance across the poles of said circuit breaker, and means for actuating said circuit breaker, including a magnet, the armature of which is connected to the circuit breaker, a second circuit for energizing said magnet whereby to effect the closing of said circuit breaker, means 10 for closing said second circuit, said means being operable by the radio tuning mechanism, said second circuit including resistance for generating heat, a thermo-sensitive element in position to be affected by said heat, and a switch operated by said element to break said second circuit after a 15 predetermined time.

4. In light control apparatus for radio receiving sets, the combination of a light and a circuit for energizing the same, a circuit breaker in said circuit, resistance across the poles of said circuit breaker, and means for actuating said circuit breaker, including a magnet, the armature of which is connected to the circuit breaker, a second circuit for energizing said magnet whereby to effect the closing of said circuit breaker, means 20 for closing said second circuit, said second circuit having two branches, means operable by the tuning mechanism of the radio for alternately completing the second circuit through said two branches, each of said branches including resistance, a thermostat placed to be affected by the heat of said resistance, and a switch operated by each thermostat for breaking said second circuit through one branch and connecting the other branch in readiness for a subsequent closing of 25 the circuit by the operation of said tuning mechanism.

5. In means for automatically controlling the degree of brilliancy of the dial lights in a radio receiving set comprising, in combination, a light, 4 and a circuit for energizing the same, a switch in said circuit, a resistance shunt across said switch and means for actuating said switch including a magnet having an armature, a second circuit for energizing said magnet and thereby moving said armature to close said switch, a radio tuning shaft, a multiple point switch operated by said shaft, said second circuit being connected through said shaft, said second circuit being connected through said multiple point switch and having two branches adapted to be alternately connected to complete said circuit by said multiple point switch, resistance elements in each of said branches, a thermostat placed to be affected by the heat of said resistance elements, and a third switch actuated selectively by said thermostats to alternately open the circuit through one branch and close the circuit through the other branch.
